UNITED STATES PATENT OFFICE.

WILLIAM A. BERNARD, OF NEW HAVEN, CONNECTICUT, ASSIGNOR TO THE WILLIAM SCHOLLHORN COMPANY, OF NEW HAVEN, CONNECTICUT.

HAND TOOL.

Application filed April 23, 1924. Serial No. 708,556.

This invention relates to hand tools and especially to tools such as pliers, pinchers, punches, wire cutters, or the like, in which lever members or other means are provided to bring together a pair of opposed co-operating jaws with more or less force. More particularly the invention relates to a tool of this character wherein provision is made for the cutting of insulated electrical conductors, and for subsequently cutting and stripping the insulation from the conductor wire enclosed thereby.

Previous to this invention, the usual practice of preparing an insulated wire for attachment to an electrical appliance or for connection with another conductor, consisted of cutting or scraping the insulation from the wire with a knife or similar tool. In the case of stranded conductors wherein a plurality of comparatively fine wires are twisted together, this method occasionally caused considerable trouble due to the cutting of the outer wires, thereby reducing the current carrying capacity of the conductor. In the case of a solid conductor, this method occasionally caused trouble due to the accidental cutting into the surface thereof to such a degree that the wire would rupture and cause an opening in the circuit when under a constant strain, causing inconvenience and possible fire hazard. To replace the hand operation of stripping a wire by the use of a knife, certain lever operated devices have been suggested which, though somewhat improving this method still retained the disadvantages above referred to relative to the mutilation of the enclosed conductor.

One object, therefore, of this invention is to provide a hand tool of this character for stripping the insulation from a conductor without the cutting means in any way affecting the surface of the conductor or mutilating the same to cause the above disadvantages.

Another object of this invention is to provide a hand tool for use in removing the insulation or covering from an enclosed wire or core, in which one of the operations is performed practically simultaneously with the other by the continued closing action of the jaws of said tool.

A still further object is to provide an efficient hand tool of this character wherein an insulated wire may be satisfactorily prepared for electrical connection with an ap-

pliance or the like, by having a portion of its insulating covering severed at a desired point and stripped from the conductor wire, both operations being performed on the same movement of the tool jaws.

Another object of this invention is to provide a tool having novel means for transmitting movement of handles or lever members to movable jaws, whereby a relative movement of the same is produced so that a relatively small force exerted on the handle or lever members will produce a relative movement of the jaws with a powerful force.

A still further object of my invention is to improve certain details of construction of tools of this character, so that a variety of operations may be performed with the same tool, preferably such operations as are usually performed together or successively in the same line of work.

Another object of this invention is the provision in hand tools of this character of improved means to cut the insulation surrounding a conductor and to strip the same from the conductor.

To these and other ends the invention consists in the novel features and combination of parts to be hereinafter described and claimed.

In the accompanying drawings:

Fig. 1 is a side view of a hand tool embodying the principles of my invention;

Fig. 2 is a view of the opposite side of the same;

Fig. 3 is a front edge view of Fig. 2;

Fig. 4 is an end view of the tool;

Fig. 5 is a view similar to Fig. 2, with the jaws of the tool open to receive an insulated wire in proper position for stripping the insulation therefrom;

Fig. 6 is a section on line 6—6 of Fig. 5;

Fig. 7 is an enlarged view of the jaws taken on line 7—7 of Fig. 5;

Fig. 8 is a view similar to Fig. 7, after the operations of cutting the insulation and stripping the same from the wire have been completed, and,

Fig. 9 is a view of the end of the tool looking in the direction of arrows 9—9 of Fig. 7, showing the relation and form of the insulation cutting and stripping means.

The hand tool illustrated in the drawings may be termed a wire insulation stripper, and as shown embodies the principles of my invention. This tool comprises a pair of

jaws 10 and 11 arranged in opposed relation and adapted by the use of suitable operating means to be parallelly moved relatively to each other to cause the opposing working surfaces to co-operate. The jaws are provided with rearwardly extending shank portions 12 and 13, respectively. The jaws 10 and 11, with the respective shank portions 12 and 13, are superimposed one upon the other and therefore in operation, each slides relatively to the other with their adjacent surfaces in contact.

The operating means provided for causing the movement of the jaws as above described, consists of a pair of handle members 14 and 15, and a pair of links 20 and 21. The handle members 14 and 15 are pivoted together and to the jaw 11 by suitable means, such as a bolt or screw 16. The bolt 16 passes through both the jaw shank portions 12 and 13, passing through a restricted opening 17 in the shank portion 13 and an elongated slot or opening 18 in the portion 12, whereby the jaw 10 is allowed longitudinal movement relatively to the jaw 11. The pair of links 20 and 21 are pivotally secured together and to the shank portion 12 by a bolt or screw 19. The bolt 19 passes through both the shank portions 12 and 13, passing through a restricted opening 22 in the shank portion 12 and an elongated opening 23 in the portion 13, whereby the jaw 11 is allowed longitudinal movement relatively to the jaw 10. The other end of each of the links 20 and 21 is pivotally secured to the handle members 14 and 15 at 24 and 25, respectively.

The above structure comprising the operating means by which the jaws 10 and 11 may be operated, causes parallel movement thereof as well as creates a more or less powerful action when the jaws are drawn together or closed, the parallel movement being obtained by reason of the fact that both the pivot points and bolts 16 and 19 act as guiding means as well as moving means for the jaw extensions 12 and 13, the bolt 16 acting to guide the extension 12 and move the extension 13 while the bolt 19 acts to guide the extension 13 and to move the extension 12. A powerful closing action is created because of the connecting arrangement of the handle members 14 and 15 in the links 20 and 21, which are so arranged that the combination thereof forms a double toggle, wherein the operating force is applied at the points 24 and 25, respectively. One toggle consists of the linked member 20 and the portion of the handle member 14 lying between the pivot 24 and the bolt 16, while the other toggle consists of the link member 21 and a portion of the handle member 15, lying between the pivot 25 and the bolt 16.

The jaws 10 and 11 extend laterally be-

yond the shank or leg portions 12 and 13, respectively, at each side thereof and with the shank or leg portion form, what might be termed as a whole, a pair of T shaped jaws. A lateral extension 30 at one side of the jaw portion 10 is provided with a cutting or shearing edge 31, which is opposed and co-operates with a similar extension 32 having a cutting or shearing edge 33, provided upon the jaw portion 11. Upon the closing of the jaws these shearing edges pass each other, as shown in Fig. 3, and are, therefore, adapted to shear or cut a wire or the like placed therebetween. The lateral extension 40 at the other side of the jaw portion 10 is provided with means to cut and strip the insulation from an insulated electrical conductor or wire, or to similarly remove the outer covering from an inner member or core of a composite structure similar to an insulation covered electrical conductor. Similar means co-operating with the above is provided in the lateral extension 41 of the jaw portion 11. As shown in this instance, a plurality of such means are provided as clearly shown in the drawings at 42, 43 and 44 and may be operated to remove the insulation from a relatively large, medium or relatively small wire, respectively, depending upon requirements. As each of the insulation removing means is of similar form with the exception of being adapted to operate upon different sized conductors, like reference characters will be used to designate like surfaces, cutting edges and operative parts thereof.

The insulation removing means 42, 43 and 44 includes a substantially semi-circular groove 45, formed in the jaw portion 10, with a similar groove 46 formed in the jaw portion 11. These grooves preferably extend longitudinally with respect to the longitudinal axis of said tool across the jaw portions and are in alignment with each other whereby they register when the jaws are closed and form a clearance opening for the conductor or wire and being of a diameter sufficient to permit the conductor or wire to be enclosed thereby during the stripping operation. The jaw portions 10 and 11 are cut away as at 47 and 48, whereby shoulders 49 and 50 are formed. The material at each side of the cut away portions 47 and 48 is shaped to provide cutting edges 51 and 52 in the jaw portion 10, and 53 and 54 in the jaw portion 11. The cutting edges 51 and 52, and 53 and 54, forming respectively a pair of cutting edges on each jaw and which extend substantially lengthwise thereof and longitudinally with respect to the longitudinal axis of the tool, are flared outwardly from the respective shoulders 49 and 50 to facilitate the longitudinally directed shearing action required thereof. In addition to these cutting edges, other

cutting edges 55 and 56 are formed in the jaw portion 10, one edge on either side of the groove 45, and cutting edges 57 and 58 are formed in the jaw portion 11, one edge on either side of the groove 46.

At the extreme outer edge of the jaw portions 10 and 11 a guide member 59 is provided to insure that the jaw portions 10 and 11 do not spring apart when in operation 10 and which is especially useful for this purpose when operating upon heavy or large sized wire requiring considerable force. It is obvious, however, that the use of such a part is optional when only one installation 15 removing means is provided in such a tool. For a similar purpose relative to the cutting or shearing portions 30 or 32, a slot 60 is formed in the jaw portion 11 which straddles the body portion 61 and is engaged beneath 20 the head 62 of a headed member 63, mounted in proper position upon the jaw portion 10 for such engagement.

The operation of the insulation removing means will now be described and reference 25 is directed especially to Figs. 5, 7 and 8, wherein an insulated electrical conductor or the like 70, is shown in various steps of having the insulation or covering 71 removed from the wire or core 72. The insulation 30 covered wire or core is placed between the jaws 10 and 11, say within the co-operating insulation removing means 43, as shown in Figs. 5 and 7. The jaws, by the proper manipulation of the handle members 14 and 15, 35 are drawn toward each other in a direction longitudinally with respect to the longitudinal axis of the tool with considerable force as above described. This action causes the cutting edges 51 and 52 of the jaw portion 40 10 and the opposing edges 53 and 54 of the jaw portion 11 to cut into and through the insulation 71, but due to these edges being spaced apart the required amount, for the particular wire or core to be uncovered, by 45 the respective grooves 45 and 46, the wire or core is not acted upon by the aforesaid edges and so is not nicked, cut or marred. The jaw closing action is continued resulting in the shoulder 49 and the side cutting edges 55 and 56 of the jaw portion 10 and the shoulder 50 and the side cutting edges 57 and 58 of the jaw portion 11 being brought into 50 contact with the insulation or covering 71, whereby the same is cut at the sides by the aforesaid cutting edges. At this time, the portion 73 of the insulation (see Fig. 8) is 55 substantially wholly severed from the remainder and is engaged by the shoulder 49 and forced downwardly and from enclosing 60 engagement with the wire or core 72 by the continued closing operation of the jaws. During this operation the shoulder 50, which is in engagement with the remainder of the insulation 71, prevents the 65 movement thereof and holds the conductor

substantially stationary. The wire or core 72 is slightly bent and is enclosed within the opening formed by the registering grooves 45 and 46. The jaws are then opened by a reverse movement of the handle 70 members and the conductor is removed therefrom with an end of the same having a portion of the insulation removed therefrom and the wire or core in a bare condition for suitable connection with any desired 75 electrical appliance.

I do not limit myself to the exact details shown in this my preferred form of hand tool, nor to the specific use thereof, as described above, as the same is capable of 80 many modifications and variations which will lie within the spirit of the invention and the scope of the appended claims.

What I claim is:

1. A hand tool comprising a pair of superimposed cooperating jaws, an extension on each of said jaws, means to draw said jaws toward each other comprising a toggle, a pivot pin connecting one link of said toggle with one jaw, said pivot pin passing 90 through the other jaw, a pivot pin connecting the other link of said toggle to the extension of the other jaw, said second mentioned pivot pin passing through the extension of said first mentioned jaw, each of 95 said pivot pins acting as a guide for one of said jaws during its movement.

2. A hand tool comprising a pair of superimposed cooperating T shaped jaws each having a leg portion, operating handles for 100 said jaws, a pivot pin passing through both of said jaws to connect said handles to one of said jaws, a link pivoted to each of said handles, a pivot pin passing through the leg portion of both of said T shaped jaws to 105 connect said links together and to the leg portion of the other of said T-shaped jaws.

3. A hand tool having a pair of superimposed cooperating jaws, each of said jaws being provided with an extension, a pair of 110 handle members pivoted together and to one of said jaws by a common pivot, said handle pivot passing through an elongated opening in the other of said jaws, a pair of links pivoted together and to the extension of the other of said jaws by a common pivot, said link pivot passing through an elongated opening in the extension of the first mentioned jaw, said links also respectively connected to said handles.

4. In a hand tool, a pair of co-operating jaws, rearwardly directed extensions upon each of said jaws, said extensions and jaws being in superimposed relation to each other, 115 handle members for operating said jaws, a pivoting member connecting said handle members together and to one of said jaws, link members respectively connected to each of said handle members, a pivoting member 120 connecting said link members together and 125

to the extension of the other of said jaws, said pivoting members respectively co-operating with the second mentioned jaw and the extension of the first mentioned jaw within elongated openings therein to guide the jaws in their opening and closing movements.

5. In a hand tool, a pair of parallel operating cutting jaws, means to move said jaws toward each other, said jaws being adapted to cut through the insulation about the wire of an insulation covered conductor, and means to subsequently strip the severed portion of said covering from the wire while said cutting jaws are being moved toward each other.

6. In a hand tool, a pair of jaws, means to move said jaws toward each other, and means on said jaws to sever a portion of an exterior covering enclosing a core member from the remainder when said jaws are moved toward each other, and means operable to strip the severed covering from the core member during a continued movement of said jaws in the same direction.

7. In a hand tool, a pair of cutting jaws, means to move said jaws toward each other, and means on said jaws co-operating while they are being moved toward each other after having cut through the covering about a core member, to remove the severed covering from said core.

8. In a hand tool, a pair of cutting jaws slideable one upon the other to sever the covering from a core member, a pair of operating handles connected to said jaws, and cooperating means upon each of said jaws to subsequently remove the severed covering from said core member during the operation of said jaws by said handle members to draw said jaws toward each other into a superimposed position.

9. In a hand tool, a pair of parallel operating jaws, means to operate said jaws, and means to remove the covering from a core member, said covering removing means comprising a pair of cutting edges in co-operative position upon each jaw whereby a portion of the covering about the core member is severed from the remainder when said jaws are moved toward each other, and a shoulder between each of the cutting edges of each pair to cause the severed portion of the covering to be forced from the core when the aforesaid movement of said jaws is continued.

10. In a hand tool, a pair of jaws slideable one upon the other, a pair of operating handles, and means to remove the covering from a core member while said jaws are being moved in a direction toward each other substantially transversely of said core member, said covering removing means comprising a pair of spaced apart cutting edges in co-operative position upon each jaw, and a

shoulder between the cutting edges of each pair to remove the covering from the core member.

11. In a hand tool, a pair of jaws slideable one upon the other, operating means for said jaws, co-operating means on each of said jaws comprising a pair of cutting edges extending lengthwise of the tool, and a shoulder disposed between the cutting edges of each jaw.

12. In a hand tool, a pair of jaws, operating means for said jaws whereby said jaws are caused to approach each other in parallel co-operating movement, cooperating means on each of said jaws comprising a pair of cutting edges extending lengthwise of the tool, and a shoulder disposed between said cutting edges whereby the covering about a core member may be first severed and then removed.

13. In a hand tool, means comprising two co-operating pairs of cutting edges adapted to straddle a covered core member, co-operating shoulders between the cutting edges of each pair, and means to successively move said pairs of cutting edges and shoulders toward each other whereby a portion of the covering about the core member is first severed by said edges and then removed from the core by said shoulders.

14. In a hand tool, a pair of jaws provided with two co-operating pairs of cutting edges adapted to straddle a covered core member, co-operating shoulders between the cutting edges of each pair, a groove in each jaw extending from each of said shoulders, and means to operate said jaws whereby said pairs of cutting edges and shoulders will move toward each other to sever the covering about the core and remove a portion thereof from the core, said grooves registering to present a clearance opening for the core when the jaws are so operated.

15. In a hand tool, a pair of jaw members slideable one upon the other, operating means for said jaw members, each of said jaw members having a groove extending longitudinally with respect to the longitudinal axis of said tool, said grooves registering when said jaw members are in superimposed relation, a shoulder formed at the termination of the grooves in said jaw members, and a cutting edge adjacent each side of the shoulder upon each jaw member, said cutting edges extending longitudinally with respect to the longitudinal axis of said tool beyond said shoulders.

16. In a hand tool, a pair of jaw members, operating means for said jaw members, each of said jaw members having a groove extending longitudinally with respect to the longitudinal axis of said tool, a shoulder formed at the termination of each groove, and a cutting edge adjacent each side of the shoulder upon each jaw member, said cutting

edges extending longitudinally with respect to the longitudinal axis of said tool beyond said shoulders.

17. In a hand tool, a pair of jaws operable in a longitudinal direction relatively to the axis of said tool to close the same, each jaw having a lateral extension thereon, and cooperating means on the lateral extension of each of said jaws to remove the covering from a core member when said jaws are operated to close the same.

18. In a hand tool, a pair of jaws slidable one upon the other, a pair of operating handles, and means to remove the covering from a core member while said jaws are being moved in a direction toward each other, said covering removing means comprising a pair of cutting edges on said jaws and a shoulder between said cutting edges, said shoulder being longitudinally directed with respect to the direction of movement of said jaws.

19. In a hand tool, a pair of jaws slidable one upon the other, a pair of operating handles, and means to remove the covering from a core member while said jaws are being moved in a direction toward each other, said means comprising a pair of cutting edges in opposed relation upon each jaw to sever the covering, and a shoulder between the cutting edges upon each jaw to space the same apart and to remove the covering from said core member, said shoulders being in opposed relation.

35 20. In a hand tool, a pair of jaws slidable one upon the other, a pair of operating handles, and means to remove the covering

from a core member while said jaws are being moved in a direction toward each other, said means comprising a pair of cutting edges in opposed relation upon each jaw, and a shoulder between the cutting edges upon each jaw to space the same apart, said shoulders being in opposed relation, one of said shoulders being adapted to engage a severed portion of the core covering and the other of said shoulders being adapted to engage the unsevered portion to separate the same and remove the severed portion from the core member.

21. In an insulation stripper, cooperating jaws having a longitudinally directed movement with respect to the longitudinal axis of the tool, and means to move said jaws, each of said jaws being provided with means to first sever the insulation about a conductor transversely thereof, and to then strip it from said conductor longitudinally thereof when said jaws are moved toward each other in the aforesaid direction.

22. In an insulation stripper, cooperating jaws having a longitudinally directed movement with respect to the longitudinal axis of the tool, and means to move said jaws, each of said jaws having means thereon to sever the insulation about a conductor transversely thereof during a part of the movement of said jaws, and to strip the insulation from the conductor longitudinally thereof by the continued movement of said jaws in the same direction.

In witness whereof, I have hereunto set my hand this 9th day of April, 1924.

WILLIAM A. BERNARD.
